UNITED STATES PATENT OFFICE

135,392

DESIGN FOR A VEHICLE

Earl L. Schofield, Freeport, Ill., assignor to Hen-
ney Motor Company, Freeport, Ill., a corpora-
tion of Delaware

Application January 16, 1942, Serial No. 105,232

Term of patent 14 years

To all whom it may concern:

Be it known that I, Earl L. Schofield, a citizen of the United States, residing at Freeport, in the county of Stephenson and State of Illinois, have invented a new, original, and ornamental Design for a Vehicle, of which the following is a specification, reference being had to the accompanying drawings, forming part thereof.

In the drawings:

Figure 1 is a side elevational view of a vehicle embodying my new design;

Fig. 2 is a rear elevational view thereof, and

Fig. 3 is a top plan view of substantially one-half of that part of the body shown in Figures 1 and 2, the other half being a counterpart of that shown.

The other side of the vehicle has the same ornamentation as the side appearing in Fig. 1.

The dominant features of my design are shown in full lines in the drawings.

I claim:

The ornamental design for a vehicle, substantially as shown and described.

EARL L. SCHOFIELD.
